UNITED STATES PATENT OFFICE.

WILLIAM B. KING, OF WILLOUGHBY, OHIO.

TROLLEY CATCHER AND RETAINER.

SPECIFICATION forming part of Letters Patent No. 619,316, dated February 14, 1899.

Application filed November 26, 1897. Serial No. 659,827. (No model.)

To all whom it may concern:

Be it known that I, WILLIAM B. KING, of Willoughby, Lake county, Ohio, have invented certain new and useful Improvements in 5 Trolley Catchers and Retainers; and I do hereby declare the following to be a full, clear, and exact description of the invention, such as will enable others skilled in the art to which it pertains to make and use the same.

10 My invention relates to trolley-catchers or devices adapted to catch the trolley as it is projected downward by the cross or brace wires or strands which support the feed-wire in an electric railway after having left the 15 said feed-wire or trolley-wire.

My invention consists in providing a retaining device or catcher so secured and located as to be at all times in such position in relation to the trolley-pole as to prevent its return 20 to the trolley-wire after said trolley-pole has been projected downward to such an extent that its return would injure either the trolley-wire, the cross-wires, or the car, and thus hold 25 said trolley-pole regardless of the relation of said trolley-pole to the top of the car.

In the drawings, Figure I is a view in side elevation of a portion of the upper part of a car with trolley-pole and turn-table attached, showing also a device constructed according 30 to my invention secured to the turn-table in proper relative position to the trolley-pole. Figs. II and III are detached views of catchers constructed according to my invention, illustrating the same in front elevation. Fig. 35 IV is a view in side elevation of a catcher constructed according to my invention, illustrating my preferred method of securing a spring so as to operate the catching-levers.

A represents the top of the car, to which is 40 attached a reinforcing-piece B. The reinforcing-piece B may be of any preferred construction so as to properly support a base C. As illustrated in the drawings, the base C is provided with a turn-table D, which supports 45 the trolley-pole E. The turn-table D is preferably provided with suitable devices, such as springs d d, for causing the trolley E to forcibly engage the trolley-wire at its upper end, and thus make a perfectly-movable contact 50 with said trolley-wire. The turn-table D is provided for the purpose of allowing the trolley-pole to swing from one side to the other

of the car in making a turn or in switching a car from one track to the other, and in some cases is also provided so that the trolley-pole 55 may be reversed from one end of the car to the other end. The so-called "turn-table" device and also the tension device, illustrated by the spring d d, may be of any suitable and operative construction that will cause the 60 trolley-pole at its upper end to engage the trolley-wire or feed-wire forcibly or so as to make a good contact and at the same time allow of the trolley-pole swinging from one side to the other of the car, and inasmuch as 65 the constructions of these several parts are varied and inasmuch as my invention is, broadly considered, adapted to operate in connection with any of these constructions I do not wish to be limited to its application to any 70 particular construction of turn-table or trolley-supporting device or trolley.

It is a well-known fact that in cases where the trolley slips from the trolley-wire the tension device attached to the trolley projects it 75 upward with great force, and if the car is running at any speed the trolley-pole will engage or strike the trolley-wire-supporting strand and in some cases will strike quite a number of them before the car can be stopped 80 or before it is stopped, owing to the fact either that the car is running at great speed or that the trolley has slipped the trolley-wire without the knowledge of either the motor-man or conductor. Now as the trolley-pole 85 comes in contact with these cross-strands or supporting-wires it strikes them with great force, according to the speed of the vehicle or car. This in turn projects the trolley-pole downward with great force and in some cases 90 with such force as to break the roof of the car or to injure the trolley-pole, and more especially is this the case where the trolley-pole engages several of the supporting-strands and force is accumulated according to the number of the strands the trolley strikes, and it is in order to obviate this objectionable feature that I have provided a catching device 95 which retains the trolley-pole after it has once been projected downward by engaging 100 any obstacle in its path.

I will now proceed to describe the construction and operation of the catcher as it is illustrated in the accompanying drawings.

F represents a framework which is open at its upper end and preferably provided with outflaring mouth f. The frame F is preferably secured at its lower end to a block G, 5 this block G in turn in the case illustrated being provided with an orifice g for engaging the piped projection H on the end of the turn-table and being secured on said pipe H by means of a set-screw g'.
 10 In the case of a device constructed as illustrated in Fig. II, I provide two pivoted levers I J, which are so located on the vertical arms of the frame F as to project inward and downward, each lever I and J preferably extending 15 half-way across the space between the arms of the frame F. I' J' represent two vertical arms, which are preferably formed integral with the levers I and J. These arms I' J' are engaged by a spring k in such a manner as to keep the levers I J normally in the position illustrated in the drawings, but at the same time allow the said lever to open and receive the trolley-pole, and after the trolley-pole has entered the levers I and J will retain 20 the trolley-pole within the catcher, inasmuch as it is impossible for the levers I and J to open upward on account of the arms I' and J' engaging the sides of the vertical arms of the frame F.
 25 As illustrated in Fig. III of the drawings, the catcher is provided with one stationary arm L, which is preferably formed integral with one of the vertical arms of the frame F, the other arm J being movable and constructed similar to the arms or levers illustrated in Fig. II, with this exception, that instead of using a spring to operate the lever J to a closed position the weight of the arm J' is depended upon to perform this function. I 30 have also shown in this figure a means for releasing the trolley-pole from the catcher after the car has been stopped, and this consists in a suitable rope or cable M, secured at one end to the arm J, as illustrated in Fig. 35 III, the said rope or cable passing over a pulley or sheave m, preferably secured to the frame F, the rope or cable passing from thence over the top of the car to a position to be reached by the operator when it is desired to 40 replace the trolley in engagement with the trolley-wire.
 45 While I have shown and described the above construction as best adapted for the object to be attained in connection with the peculiar 50 construction of trolley and stands illustrated, I do not wish to be confined, as I have hereinbefore stated, to this particular construction of catchers, inasmuch as modification may be made without departing from my 55 invention.
 60 The gist of my invention consists in so se-

curing and locating the catcher in relation to the trolley-pole that it will be in a position at all times to receive said trolley-pole as it is projected or forced downward.

65

What I claim is—

1. A trolley-pole-catching device comprising a base or stand to which it is connected; means secured to said base or stand, comprising a retaining device, said retaining device 70 moving with said base or stand and provided with means for catching and inclosing the trolley-pole when the same is downwardly projected, substantially as and for the purpose set forth.

75

2. The combination with a trolley-pole and its operating and sustaining stand or base; of a catching and retaining device secured to said base or stand directly beneath the trolley-pole, said retaining device adapted to embrace and hold the trolley-pole and move with the base or stand in a horizontal direction, substantially as and for the purpose set forth.

80

3. The combination with a trolley-pole, of an automatically-operated receiving and retaining device located beneath said pole and in position to receive it as it is projected downward, said catching and retaining device provided with spring-operated levers opening downward, substantially as and for the purpose 85 shown and described.

90

4. A catching and retaining device for trolley-poles of electric cars located beneath and in a vertical line with the trolley-pole, and provided with automatically-operated retaining-levers whereby when the trolley is received by the catchers it is retained until said retaining-levers have been opened or separated to release it.

95

5. In a trolley-catcher, the combination 100 with a frame open at its upper end, of one or more pivoted levers opening downward to receive the trolley and automatically closing upward to retain said trolley after it has been received, substantially as and for the purpose 105 shown and described.

105

6. In a trolley catcher or retainer, the combination with a framework open at its upper end and provided with automatically-working pivoted levers opening downward to receive the trolley and automatically closing upward to retain it, of a rope or cable secured to one of said levers whereby the catcher may be opened and the trolley released, substantially as set forth.

115

In testimony whereof I sign this specification, in the presence of two witnesses, this 13th day of November, 1897.

WILLIAM B. KING.
